[57] CLAIM

The ornamental design for a ceramic clean-up trim tool, as shown.

DESCRIPTION

FIG. 1 is a side elevational view of a ceramic clean-up trim tool showing my new design;

FIG. 2 is a side elevational view thereof with the tool rotated 90° from the position shown in FIG. 1;

FIG. 3 is an end view taken from the left side of FIG. 1; and

FIG. 4 is an end view taken from the right side of FIG. 1.
